TRAIN ORDER HOLDING DEVICE

Wiley L. White and Walter L. White, Calwa,
Calif.; said Walter L. White assignor to Wiley
L. White

Application October 14, 1941, Serial No. 414,972

2 Claims. (Cl. 258—2)

Our invention relates to a train order holding device, and more specifically to a device for delivering train orders to operators of fast moving trains without danger of injury to the persons receiving the orders.

The objects accomplished by our invention is the construction of a device for holding written orders to be delivered to operators of fast moving trains. This device is simple in construction, can be built at a small cost, can be easily installed for use and easily removed when not in use, is adjustable as to height, cannot be installed in any but a workable position, can deliver a number of messages, or orders consecutively, and in which hazard to operators of trains who take such orders is minimized. Other objects will be herein-after disclosed.

These objects are accomplished by means of the device hereinafter described, and illustrated on the accompanying drawings in which,

Fig. 1 shows a side view of the device, parts being cut away to shorten the actual length of the device, in said figure.

Fig. 2 is a view of the same device shown in Fig. 1, looking toward the front of the holding arms.

Fig. 3 is a sectional view of a fractional portion of the upright post along broken line 3—3 in Fig. 1, showing the telescoping portions of said post or support, and the means for interlocking said telescoping portions together, said figure being enlarged as related to Fig. 1.

Fig. 4 is an isometric view along broken line 4—4 in Fig. 2 showing the shape, and telescoping features of the upright support.

Fig. 5 is an enlarged view of the device showing arms for holding the written message, or order, in its normal, or inoperative position, and in broken lines showing the position in which the arms are placed when holding the written orders for delivery. In said figure portions have been cut away to show the means for attaching the arm assembly to the post, and showing expansion springs for moving and yieldingly holding the arms in an upright position.

Fig. 6 shows a portion of the device illustrated in Fig. 5 as viewed on a plane at right angles to the plane of view of Fig. 5.

Fig. 7 is an enlarged perspective view of the order holder assembly, showing fractional views of the upright post and the arms adapted for holding the written orders, and a clip spring for holding a string to which the order is attached.

Fig. 8 is a top view of the foundation block 55

having a socket therein to receive the upright post.

Fig. 8A shows the same foundation block disclosed in Fig. 8, having a modified form of socket.

Fig. 9 is a side elevation of a modified form of the device in which a plurality of pairs of arms are carried on a drum adapted to be revolved.

Fig. 10 is a top view of the revolving drum of which a sectional view appears in Fig. 9.

Fig. 11 is an enlarged view of a locking device which cooperates with the revolving drum to stop the rotation of the drum at selective positions.

Referring to the drawings, we prefer to have a permanent concrete foundation in the earth at a location near enough to the railroad track to position the device adjacent to the passing trains, the object being to permit the engineer on the engine, or other operator or conductor riding on the train to reach for, and secure the message

while the train is moving at a rapid rate. As shown in Fig. 8 foundation 22 has a socket 22A angular in shape to conform to the angular shape of the post, so that post 24 can be inserted in said socket 22A with a selected face of the post facing the track. This form is used for single tracks only. In Fig. 8A we have shown a similar foundation 22, having a modified form of socket 22B therein, which socket permits the selected face of the post to face in two opposite directions, said

direction to be selected by the employee engineering the device. The purpose of the double socket is to adapt the device to be used between double tracks, so the dispatcher can use the device for either track at will. As hereinbefore referred to, the lower end of post 24 should be shaped to fit snugly in socket 22A, so post 24 will be held upright, and loose enough so that post 24 can be easily removed when the device is not in use. Our preferred construction is to

form the socket, and the co-operating end of post 24 with a slope, except the end fitting into socket 22A, post 24 can be of uniform shape its entire length.

Post 24 has a step 24A attached near the bottom and above the sloping portion fitted in socket 22A, the object of said step 24A being to assist in pushing the post into said socket, and to hold it there, preferably by the foot of the employee, while adjusting or otherwise working with the post, or elements attached to the post.

A sliding member 23 is adapted to slide on, or telescope on post 24, as is clearly shown in Fig. 4. The purpose of this construction is to adjust the supporting post as to length. At selective heights post 24 and sliding member 23

should be locked together. This is accomplished by lock 35, shown in Fig. 3. Sliding member 23 has a hole 35A therethrough, through which lock 35 can pass. Post 24 is provided with a plurality of indentures 38 which can selectively register with hole 35A. When sliding member 23 is raised to the desired height, lock 35 can pass through hole 35A and through the selected indenture 38 and thus lock sliding member 23 to post 24.

A leaf spring 31, shown in Fig. 3, is adapted to hold lock 35 normally in an engaged relation with post 24. Handle 34, shown in Fig. 3 is adapted to be grasped to easily raise or lower sliding member 23.

Means for holding the written message or order is shown as assembly A. It consists of a main support 28 which is preferably attached to sliding member 23 by means of catches 39A attached to assembly A, which catches are adapted to engage lugs 39 attached to sliding member 23. To main support 28 is pivotally attached tubular sockets 26 and 27, the pivotal connection adapting the tubular sockets to assume the position of a continuous vertical line, and to be moved at angular relation with each other. Springs 31 and 31A are adapted to hold said sockets in the open relation described, and to move them to such open relation.

Arms 26A and 27A, which are adapted to hold the written orders to be delivered, are fastened within sockets 26 and 27, so they can be easily replaced if necessary. These arms are made of light wood or similar material so that if they accidentally strike the operator when he is grasping the written orders, the arms will break and not violently strike the operator. It is not contemplated that such striking will occur, but this provision has been made in our construction to overcome accidental occurrences.

On main support 28 we have attached a spring clamp 32. An endless string is shown as 33. The outside ends 26B and 27B of arms 26A and 27A are bifurcated. Endless string 33 is yielding held by clamp 32, and is passed over the ends of arms 26A and 27A, being held in the bifurcations described, and the string 33 is of such length that when thus threaded from spring clamp 32 to ends 26B and 27B it is in a triangular shape, and the arms 26A and 27A are angularly extended from supporting pole 23 and held taut by springs 31 and 31A. The written orders sought to be delivered is attached to string 33 between the ends of arms 26A and 27A. As this device is positioned near the track carrying the train, the engineer, conductor or operator of the train, and on the train, can extend his arm as his train is passing this device and catch the string to which the orders are attached and thus get the orders.

It will be noted that when the string is removed from the arm assembly with the written orders attached thereto, the tension of springs 31 and 31A will function to pull arms 26A and 27A to the vertical position heretofore described.

When a plurality of order holders or assemblies A or B are attached to the device as shown in Fig. 1, after the engineer first passing the device has taken the orders from assembly A, and the arms of that assembly have automatically assuming the vertical position, the engineer following in the second engine, or the conductor, or other official on the train who should receive a duplicate of the first order mentioned, can take copies of such orders from assemblies B or C in consecutive order.

Stops 41 and 41A, shown in Fig. 5, are intended to limit the radial movement of arms 26A and 27A when placed at angular relation with each other. Rod 44 is anchorage for springs 31 and 31A. Clamp 43 is adapted to hold a flash light which can be positioned to direct its rays at night on the orders to be delivered.

Prongs 64 and 65 at the bifurcated ends of arms 26A and 27A are of different lengths, so that when string 33 is pulled off of the assembly A, the string will slide off of the short prongs 65 first.

It is also noted that the arms 26A and 27A can be made of wood, or springy material, such as rubber.

In Figs. 9, 10 and 11 are shown a modified form for the delivery of a plurality of written messages or orders to a plurality of persons, either all on different sections of one moving train, or to persons on different trains. The base, the supporting post and the arm assembly A are the same as hereinbefore described. At the elevation desired on the supporting post 23 we have attached a thimble 50, which is adapted as a bearing for the use hereinafter described, which thimble can be held rigid with the supporting post by a set screw 51, screwed through the thimble and into the post on which it is carried. A drum 52 is adapted to rotate on thimble 50. A coil spring 53 within the drum provides the power to rotate the drum. On the outside periphery of the drum 52 are attached lugs 39, similar in all respects to lugs 39 shown in Fig. 5. The arm assembly A hereinbefore described is attached to lug 39. The object of the presently described device is to carry a plurality of arm assemblies A, which in this connection are designated arm assemblies A, B, C and D, as four such assemblies are shown in the drawings, although a less number or a greater number may be used.

A plurality of lugs 54, and a similar number of auxiliary lugs 54A are attached to the under face of the drum in such position that when each arm assembly, of which arm assembly A is a specimen, is positioned for the operator of the train to receive orders, a sliding stop 55 will be between lugs 54 and 54A and engaged therewith so that the drum cannot move in either direction. Holding the drum rigid in this manner is necessary by reason of the fact that the arms should be positively positioned on the drum when the delivery of the message is made. The positions of the lugs and sliding stop is shown more clearly in Fig. 11.

The sliding stop is tripped from engagement with lugs 54 and 54A in the following manner. Sliding stop 55 is attached to a plunger 56, which plunger 56 is adapted to be moved back and forth in a tube 60, said tube 60 having parts cut away to permit stop 55 to be moved. It is noted that sliding stop 55 is positioned normally directly under arm assembly A when said stop is engaged with lugs 54 and 54A. When the message and string attached is removed from the arms, the arms 26A and 27A, and the connected sockets 26 and 27 assume a vertical position. In assuming said vertical position the lower socket 27 will be forced against plunger 56 and move it, together with stop 55 attached thereto, out of engagement with lugs 54 and 54A, thus permitting the drum to rotate. Immediately on the rotation of the drum the plunger 56 is freed from the pressure from socket 27 as the rotation of the drum carries the socket away from the plunger, and plunger 56 is restored to its normal position by means of plunger spring 57, and is thus adapt-

ed to engage the next succeeding stop in its path of travel, designated 54A. As lug 54A has a sloping face for engagement with stop 55, the power of coiled spring 53 in rotating drum 52 will force stop 55 downward to engagement with lug 54, thus locking the drum in the position desired.

Arrow 62 in Fig. 11 shows the direction of travel of sliding stop 55. Arrow 61 shows the direction of travel of the drum. The message to be delivered is indicated on the drawings as 66.

In Fig. 10 are shown stops 58 and 58A which are attached to thimble 50. A lug or screw head 59 is attached to the drum, and is adapted to cooperate with stops 58 and 58A to limit the movement of the drum in its rotation. In the drawings this limitation range is three-quarters of a turn, which limitation takes care of four arm assemblies, as indicated. The stops can be changed for either more or less assemblies A as may be desired.

In this specification we have described our preferred form of construction, but the spirit of our invention covers any equivalent form of construction which can be substituted for those claimed.

Having described our invention, we claim:

1. A device of the character described comprising a support, a drum rotatably attached to said support, means for rotating said drum consisting of a coiled spring, a plurality of message holder assemblies, each assembly consisting of two light wooden arms, a bracket support or plate, said arms being pivotally hinged at one end to said bracket support or plate, said pivotal connection adapting the arms to be moved to angular relation with each other, and on an approximately straight line with each other, spring means adapted to normally return said arms from the angular position to said straight line position, an endless string yieldingly held adjacent said bracket support, and of such length that said string will engage the ends of the arms when said arms are at angular relation with each other, means for attaching a message to said string,

said message holder assemblies being attached to the periphery of the drum by means of a lug extending outwardly from the periphery of the drum, the bracket support or plate to which the arms are attached, having thereon a catch adapted to cooperate and engage with the lug so that the arm assembly can be easily attached to the drum and easily removed therefrom, means for intermittently stopping the rotation of the drum and locking it in selected positions.

2. A device of the character described comprising a support, a drum rotatably attached to the support, spring means for rotating the drum, a plurality of message holder assemblies, each assembly consisting of two arms pivotally hinged at one end to a plate, the two arms being adapted to be moved on the pivotal connection to angular relation with each other and on an approximately straight line with relation to each other, spring means adapted to normally return said arms from the angular position to the straight line position, means for attaching the plate and assembly to the periphery of the drum, a string yieldingly attached to the ends of the arms, the string being of such length that it is taut when the arms are at angular relation with each other, means for attaching a message to said string, means for locking the drum at selective positions during rotation consisting of lugs attached to the drum spaced distances apart and concentric with the drum, a sliding stop attached to the support and adapted to slide within the path of travel of the lugs, said sliding stop being adapted to engage any one of said lugs, spring means adapted for holding the sliding stop in engagement with the lugs, means for disengaging the sliding stop with the lugs consisting of a plunger attached to the sliding stop, one arm of each message holder assembly being adapted to engage the plunger when the arms of said assembly assume a straight line relationship.
